(57) **CLAIM**

The ornamental design for an attachment sleeve for a vibrator head, as shown and described.

DESCRIPTION

FIG. 1 is a view in side elevation of the attachment sleeve, showing my new design.

FIG. 2 is a view in side elevation from the back thereof, rotated 180° from that shown in FIG. 1.

FIG. 3 is a view in side elevation thereof, rotated 90° from that shown in FIG. 1.

FIG. 4 is a view in side elevation thereof, rotated 180° from that shown in FIG. 3.

FIG. 5 is a top plan view thereof; and,

FIG. 6 is a bottom plan view thereof.
